UNITED STATES PATENT OFFICE.

ALBERT SLATEN, OF MINNEAPOLIS, MINNESOTA.

BUTTER CUTTER.

Application filed July 31, 1926. Serial No. 126,243.

This invention relates to butter cutting devices, and the primary object is to provide a practical, efficient and comparatively simple machine for supporting and advancing a cake of butter, progressively cutting the same up into "pats" or "chips", and particularly for separating the "chips" or pieces as they fall from the main cake, so that the small pieces will not stick together and may easily be taken from the ice jar or bowl into which they are usually dropped, and in which they are kept until needed, as in cafes, restaurants, lunch rooms, etc.

Further and more specific objects will be disclosed in the course of the following specification, reference being had to the accompanying drawings, wherein:

Fig. 1 is a sectional elevation on a longitudinal plane substantially through the center of the machine.

Fig. 2 is an enlarged detail view, partly in section, of the butter "chip" thickness adjusting device.

Fig. 3 is a left side elevation of the machine, with upper and lower portions thereof broken away.

Fig. 4 is a front end elevation of the machine, with the cutter head partly lowered.

Fig. 5 is a rear end elevation, portions being broken away.

Fig. 6 is a front elevation, similar to Fig. 4, but showing the cutter head in its uppermost position.

Referring to the drawings more particularly and by reference characters, 7 designates a hollow, main, cast frame, having legs 8, and having depending bearings 9 and 10 in which are respectively journaled shafts 11 and 12, the latter of which is provided with a hand crank 13. The frame is further provided with a trough 14, in which is slidably retained the block of butter A, and the block A is progressively advanced toward the cutting mechanism, at the front of the machine, by a traveller 15, having a pawl 16, engageable with a longitudinally reciprocable, toothed rack bar 17. The bar 17 has a lug 19, connected by a link 20, to a lever 21, pivoted as at 22 to the main frame, and a spring 23, acting on the lever 21, tends to hold the bar 17 rearwardly, with the lug 19 against a stop pin 24. The stop 24 is adjustable, so as to regulate the stroke length of the bar 17, and thus effects an adjustment to the thickness of the "chips" cut from the butter block by the vertically re-

ciprocating cutter head. The stop adjusting device is illustrated in Figs. 1, 2 and 5, and may be described as follows: The stop 24 is slidably and non-rotatably secured in a collar 25, secured to the frame 7, and has a projecting pin 26 which extends into a curved slot 27 in a sleeve 28 trunnioned on the collar 25. The sleeve 28 has a crank arm 29 in the end of which is threaded a knob or handle 30 having a point 31 adapted, by turning the knob, to be secured in any one of a semi-circular series of perforations or recesses 32 in the back wall of the main frame 7. Thus, it will be seen, that by releasing the point 31 and resecuring it in the recess 32 desired, the back stroke of the rack bar 17 and consequently the advance movement of the butter cake may be adjusted so that the thickness of the butter chips may be easily regulated at will. The successive forward movements of the cutter bar 17 are effected by the lever 21, which is periodically tripped by a pin 33 on a cam 34, carried by the shaft 12. The edge of the cam 34 is engaged by a roller 35 of an arm 36 of the shaft 11, and the shaft 11 is further provided with a pair of side arms 37, connected by a U-shaped link yoke 38 to the cutter head which it operates. The cutter head is raised, after each downward or cutting movement, by an upward movement of the arms 37, and this is effected by a spring 39, connecting an arm 40 of the shaft 11 to the main frame, and a cam 41, carried by the shaft 12 and engageable with the roller 42 of an arm 43, extending from the shaft 11. Either or both the cam and spring may be used. Thus, it will be seen that the vertical, reciprocating motion of the cutter head is synchronized with the successive advances made by the traveller head 15.

To stop the advance movement of the member 15, when the supply of butter is exhausted, and to provide means for readily returning the head to its rearward or initial position. I have provided the pawl 16 with a laterally arranged lifting lever 44. When this lever approaches its foremost position, as indicated by the dotted lines in Fig. 3 it is raised by a permanent pin 45, thus disengaging the pawl 16, and to return the pusher head 15 to its rearward, initial position, it is only necessary to grasp and pull the lever rearward, while in its raised position, and then releasing it so that the pawl 16 will reengage the teeth of the rack 17.

The butter cutting and "chip" separating mechanism, which is of primary importance in the present instance, may be described as follows:

5 Permanently secured in the frame 7, and at the front end of the trough 14, is a pair of spaced, vertical standards 46, between which is slidably arranged a frame 47, having crossed wires 48 and 49, through which

10 the butter cake is forced by the head 15 so as to divide it into four equal cuts, A¹, A², A³, and A⁴. Only two crossed cutting wires are shown, but it is obvious that any number may be employed, depending upon the 15 size of the cake of butter, and the size of chips desired. When the cutter head, soon to be described, is removed, the frame 47 may be pulled out, upwardly, for cleaning purposes.

19 The cutter head consists of a plate 50, having lateral flanges 51 which guide on the standards 46, so that the head may be moved up and down. This head may also be quickly removed from the standards 46, for 23 cleaning purposes, by being detached from the yoke 38, said yoke being secured to the cutter head by a spring clip 52.

The cutter head is further provided with a diagonally disposed cutting wire 53, which 29 operates in a vertical plane immediately adjacent to the plane of the cross wires 48 and 49, so that when the butter cake is pushed a predetermined distance through the wires 48, 49, the resulting chips or pats, A¹, A², 35 A³, and A⁴, are severed from the cake A, thus forming the desired pieces for table use. The tautness of the wire 53 may be adjusted by suitable means such as an adjusting screw 54.

40 I am aware of the fact that butter cutters have previously been designed which embody the broad principle of pressing a butter cake through crossed wires and then severing the projected chips to form the desired shaped pieces. In all of such instances that 45 have come to my attention, however, there has been no provision for positively segregating and individually delivering the cut chips, with a result that the chips will stick 50 together, especially in warm weather, and are difficult to separate when about to be served to customers. But if the chips can be kept separated and be separately delivered to the ice container or ice water bowl, this difficulty is not ordinarily experienced.

55 In order to segregate the pieces so that they will not stick together as they leave the main cake, I provide the cutter head plate 50 with a pair of separating fingers 55 and 60 56 which are laterally spaced and offset, one higher than the other. The lower ends of these fingers pass, with the plate 50, into the curf made by the wire 53, and their upper ends are outwardly or forwardly curved 65 (see Fig. 1), so as to tilt the pieces for-

wardly. To assist the fingers 55 and 56 in their work I also provide the cutter head with a transverse, forwardly spaced bail 57, which is offset as at 58 so that one half is lower than the other, and under the projecting end of the butter cake I arrange a guard or bracket 59 to prevent the butter chips A³ and A⁴ from falling directly downward.

70 The operation of the cutter head parts 75 may be briefly described, as follows:

As the cutter head moves downward the wire 53 will first completely sever the chip A², due to the inclined position of the wire. The finger 55 will now tilt this chip forwardly over the corresponding or lower portion of the bail 57, and the loosened chip will be dropped over the bail and into a suitable container (not shown) below. In the meantime the other end of the wire 53 has 80 cut a substantial curf behind the chip A¹, and as this chip is completely severed it is delivered over the higher end of the bail, and follows the chip A² into the bowl below, while the lower end of the wire 53 continues 85 into chip A⁴. The chips A⁴ and A³ are formed and delivered in like fashion, except, that they are held in place by the guard 59 until the action of the fingers 55 and 56 is completed. Thus the four chips 90 95 are separately and successively delivered from the machine.

95 At this point the cam 41 reengages the roller 42, the cutter head is lifted by the 100 arms 37, the pin 33 actuates the lever 21 to move the traveller head 15 a step forward, the butter cake is forced the necessary distance through the cross wires 48 and 49, and the cutter head is again in readiness to repeat the operation above set forth.

105 It is understood that suitable modifications may be made in the general design and structural details of the invention as herein shown and described, provided, however, that said modifications come within the spirit and scope of the appended claims.

Having now therefore fully shown and described my invention, what I claim to be new and desire to protect by Letters Patent is:

110 1. In a machine for cutting a block of butter into relatively small pieces, the combination including means for longitudinally dividing the block into sections, means for transversely dividing the sections into the desired pieces, and means independent of both said dividing means but movable together with the second dividing means for separating the sections from each other and individually delivering them from the machine, said separating means comprising a pair of finger members 115 one of which is vertically offset with respect to the other.

120 2. In a machine for cutting a block of butter into relatively small pieces, the com-

- bination including means for longitudinally dividing the block into sections, a cutter head, slidably carried by the machine, and having an element for transversely cutting the sections into pieces, and means, carried by the cutter head independent of the element, for separating the pieces, as they are cut, and delivering them from the machine, said separating means comprising a pair of finger members one of which is vertically offset with respect to the other. 5 60
3. In a machine for cutting a block of butter into relatively small pieces, the combination including means for longitudinally dividing the block into sections, a cutter head, slidably carried by the machine, for transversely cutting the sections into pieces, and fingers, carried by the cutter head for directing the pieces away from the butter block as they are cut, said fingers being vertically offset with respect to each other. 10 65
4. In a machine for cutting a block of butter into relatively small pieces, having means for longitudinally dividing the block into sections, and a cutter head slidably carried by the machine, for transversely cutting the sections into pieces, the combination of outwardly directed fingers and a bail associated therewith, carried by the cutter head, for receiving and delivering the butter pieces as they are successively severed from the butter block. 15 70
5. In a machine for cutting butter having a guide for supporting a block of butter, a frame at one end of the guide and having crossed cutting members through which the block of butter is moved to divide it longitudinally into sections, and a cutter head operating in a plane adjacent to the frame for transversely cutting the sections into small pieces, the combination of means carried by the head for successively separating the cut pieces and delivering them away from the remaining pieces, said means comprising a pair of fingers one of which operates in advance of the other. 20 75
6. In a machine for cutting butter having a guide for supporting a block of butter, a frame at one end of the guide and having crossed cutting members through which the block of butter is moved to divide it longitudinally into sections, and a cutter head operating in a plane adjacent to the frame for transversely cutting the sections into small pieces, the combination of means carried by the head for successively separating the cut pieces and delivering them away from the remaining pieces, said means comprising a pair of outwardly curved and transversely spaced fingers one of which is higher than the other. 25 80
7. In a machine for cutting butter having a guide for supporting a block of butter, a frame at one end of the guide and having crossed cutting members through which the block of butter is moved to divide it longitudinally into sections, and a cutter head operating in a plane adjacent to the frame for transversely cutting the sections into small pieces, the combination of means carried by the head for successively separating the cut pieces and delivering them away from the remaining pieces, said means comprising a pair of outwardly curved and transversely spaced fingers one of which operates in advance of the other. 30 85
8. In a machine for cutting butter having a guide for supporting a block of butter, a frame at one end of the guide and having crossed cutting members through which the block of butter is moved to divide it longitudinally into sections, and a cutter head operating in a plane adjacent to the frame for transversely cutting the sections into small pieces, the combination of means carried by the head for successively separating the cut pieces and delivering them away from the remaining pieces, said means comprising a pair of outwardly curved and transversely spaced fingers, one of which is higher than the other. 35 90
9. A butter cutter having a main frame for supporting a block of butter, a pair of standards at one end of the frame, a cutter frame detachably secured between said standards, through which the butter block is moved to divide it longitudinally, and a cutter head slidably carried by the standards for dividing the butter block transversely, the combination of means including a substantially U-shaped yoke for actuating the cutter head. 40 95
10. A butter cutter having a main frame for supporting a block of butter, a pair of standards at one end of the frame, a cutter frame detachably secured between said standards, through which the butter block is moved to divide it longitudinally, and a cutter head slidably carried by the standards for dividing the butter block transversely, the combination of means including a substantially U-shaped yoke for actuating the cutter head, said yoke being detachable with respect to the cutter head. 45 100
- 50 105
- 55 110

In testimony whereof I affix my signature.

ALBERT SLATEN.
